(57) **CLAIM**

The ornamental design for a captive screw, as shown and described.

DESCRIPTION

FIG. 1 is a side perspective view of a captive screw with a self-clinching retainer in a non-fastened position, all remaining sides being identical.

FIG. 2 is a side perspective view of a captive screw with a self-clinching retainer in a fastened position, all remaining sides being identical.

FIG. 3 is a bottom perspective view shown in FIG. 1.

FIG. 4 is an alternative top plan view of the captive screw showing a cross driver recess.

FIG. 5 is an alternative top plan view of the captive screw showing a combination slotted/cross driver recess.

FIG. 6 is an alternative top plan view of the captive screw showing a slotted driver recess.

FIG. 7 is an alternative top plan view of the captive screw showing a slotted six-lobed driver recess; and,

FIG. 8 is an alternative top plan view of the captive screw showing a six-lobed driver recess.
